THOMAS A. FOX, OF NEWARK, NEW JERSEY, ASSIGNOR TO THE STEFFENS-AMBERG CO.,
A CORPORATION OF NEW JERSEY.

SPUD HIP-LOOP FOR HARNESS.

1,167,812.

Specification of Letters Patent.

Patented Jan. 11, 1916.

Application filed February 27, 1912. Serial No. 680,315.

To all whom it may concern:

Be it known that I, THOMAS A. FOX, a citizen of the United States, residing at Newark, in the county of Essex and State of New Jersey, have invented certain new and useful Improvements in Spud Hip-Loops for Harness; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention has reference, generally, to improvement in harness; and, the present invention relates, more particularly, to a novel harness-attachment for the hip-straps of harness, and which harness-attachment is 20 hereinafter termed as the spud hip loop.

The present invention has for its principal object to provide a novel, neat, and simply constructed spud hip loop of the general character hereinafter set forth having 25 for its purpose to collect the several short members of the hip-strap, and also to provide a device for the reception and retention of the driving reins, when the latter hang loose, so as to prevent the lines from being 30 caught beneath the tail of the horse.

With these objects in view, the invention consists, primarily, in the novel spud loop hereinafter more fully set forth; and, the invention consists furthermore, in the novel 35 arrangements and combinations of the several parts of the device, all of which will be hereinafter more fully described, and then finally embodied in the clauses of the claim which are appended to and which form an 40 essential part of this specification.

The invention is clearly illustrated in the accompanying drawings, in which:—

Figure 1 is a face view of a spud hip loop and portions of the several members of 45 a hip-strap shown in their collected or assembled relation with the said hip loop, and illustrating in connection therewith part of a driving rein or line in its supported relation with the said hip-loop. Fig. 2 is a 50 face view of the said spud hip loop in its detached relation; and Fig. 3 is a side elevation of the same. Fig. 4 is a face view of a slightly modified construction of a spud hip loop, the same, however, still embodying 55 the principles of the present invention; and

Fig. 5 is a transverse vertical section of the same, said section being taken on line 5—5 in said Fig. 4, looking in the direction of the arrow α .

Similar characters of reference are employed in the said above described views, to indicate corresponding parts.

Referring now to the said drawings, the reference character 1, indicates the upper main portion or back strap and 2 and 3 represent the short members forming the double or split hip-strap of a harness, all of which are collected and secured in their assembled relation by means of a spud hip loop 4 made according to the principles of the present invention.

The spud hip loop comprises a ring-shaped main body, as 5, preferably of oval or elliptical configuration, although the same may be of any other desirable shape, and the said body being of any suitable cross-section, preferably circular. Extending upwardly, and suitably curved so as to extend rearwardly out of the plane of the said main body 5, is a rein or line-supporting member or finger 6, said member or finger being integrally connected with the said main body at the one side thereof, as at 7. The said member or finger 6, as will be evident, may be of any suitable shape and configuration, the outer end-portion thereof being preferably rounded and made somewhat heavier, than that portion of the said member or finger where it is connected with the said main body-portion 5, as clearly shown in the several figures of the drawings.

In the construction of spud hip loop illustrated in Figs. 4 and 5 of the drawings, the device consists of a main body 8 of a suitable ring-shaped configuration, the said main body being provided with a centrally disposed and longitudinally extending cross-bar or member 9, the cross-section of which is preferably circular, and the end-portions of the said cross-bar or member 9 being integrally connected with the opposite side-portions of said main body 8. Projecting upwardly from the said cross-bar 9, preferably at the central portion thereof, and suitably curved so as to extend rearwardly out of the plane of the said main body 8, is a rein or line supporting member or finger 10, the said member or finger 10 being integrally connected with the said cross-bar or member 9. The said member or finger 10 is

also, preferably, of the same general configuration as the member or finger 6, shown in connection with the form of spud hip loop illustrated and described in connection with 5 Figs. 1, 2 and 3 of the drawing; but, it will be understood, that the said supporting member or finger 10 may be of any other suitable shape.

The manner of attaching the back-strap 1 10 and the double hip-strap members 2 and 3 permanently to the spud hip loop 1 is clearly shown in Fig. 1 of the drawings. The strap 1 is formed with an open portion 12, so that its ends, when passed around the ring- 15 shaped body 5 will lie upon opposite sides of the member or finger 6, so that said finger, when the harness has been placed upon the horse, is vertical, or substantially so. The two members 2 and 3 of the double 20 or split hip-strap are permanently secured to the said ring-shaped body 5 in the manner shown in said Fig. 1 of the drawings, and the manner of supporting the driving reins or lines 11 upon the member or finger 6 is 25 also clearly shown in said Fig. 1.

I claim:—

1. A spud hip loop for the hip-straps of harness comprising a ring-shaped main body of oval configuration flat so that it will 30 lie in a single straight plane, and an upwardly projecting rein-supporting finger ex-

tending centrally and transversely from said oval ring-shaped body in a plane at right angles to the single straight plane of the said oval ring-shaped body, said finger comprising an upwardly extending end-member integrally connected with the said ring-shaped body and curved at its free end-portion forwardly in a manner substantially as and for the purposes set forth. 35

2. A spud hip loop for the hip-straps of harness comprising a ring-shaped main body of oval configuration flat so that it will lie in a single straight plane, and an upwardly projecting rein-supporting finger extending 40 centrally and transversely from said oval ring-shaped body in a plane at right-angles to the single straight plane of the said oval ring-shaped body, said finger comprising an upwardly extending end-member integrally 45 connected with a marginal part of said oval ring-shaped body and curved at its free end-portion forwardly and beyond the outer marginal surface portion of said part, substantially as and for the purposes set forth. 50

In testimony, that I claim the invention set forth above I have hereunto set my hand this 24th day of February, 1912.

THOMAS A. FOX.
